UNITED STATES PATENT OFFICE.

FRED SWAN, OF MARIETTA, OHIO.

CLAMPING RING FOR EXPANSIBLE TOOLS.

Application filed February 9, 1924, Serial No. 691,725. Renewed April 3, 1925.

To all whom it may concern:

Be it known that I, FRED SWAN, a citizen of the United States, residing at Marietta, in the county of Washington and 5 State of Ohio, have invented certain new and useful Improvements in Clamping Rings for Expansible Tools, of which the following is a specification, reference being had to the accompanying drawings, forming 10 a part thereof.

My invention relates to clamps for holding the cutters of expansible well drilling tools in closed position, and has for its object to provide a device for this purpose 15 adapted to rest upon the upper end of casing when the tool is in the well and to fit over the cutters as the tool is withdrawn through the casing and clamp them in closed position and so hold them until the tool 20 is again introduced into the casing.

In under reamers of Swan under reamer type and other under-reamers and expansible drills in which the cutters move from collapsed position into expanded operating 25 position by being drawn upward after the tool is lowered below casing, to ride upon a wedge or are otherwise drawn up so that their inner face rest against fixed abutments, it is necessary in order to introduce the tool 30 into the well casing to draw the cutters down on the tool body and hold them in collapsed position until the tool is lowered into the upper end of the casing, and whenever the tool is withdrawn from the casing the 35 operation of drawing down the cutters and securing them in collapsed position must be repeated.

It is the object of my invention to provide a device which will rest upon the upper 40 end of the casing in position to serve as a protection for the threads of the coupling at such upper end and which, as the under-reamer or other collapsible cutter tool is withdrawn, will extend about the cutters 45 and hold them against springing out as they would otherwise do as they are drawn up above the upper end of the casing.

With the objects above indicated and other objects hereinafter explained in view, 50 my invention consists in the construction and combination of elements hereinafter described and claimed.

Referring to the drawings:

Figure 1 shows in vertical sectional view a portion of the upper end of a well casing showing a clamp embodying my invention in position ready to operate to clamp 55 the cutters of the under reamer shown within the casing,

Figure 2 is a side view of the same showing the under reamer lifted above the upper end of the casing,

Figure 3 is an end view of the under reamer within the well casing,

Figure 4 is a side view of the upper end 65 of a well casing showing how the clamp may be placed in position for use.

Figure 5 is a vertical sectional view of the upper end of a well casing showing a modified form of clamp in position. 70

Figures 6, 7 and 8 show the clamp in top plan, side elevation and vertical section respectively.

In the drawings 1 indicates the upper section of a well casing having at its upper end the usual threaded coupling ring 2. 75 3 indicates an under reamer having the bits or cutters 4, 4, in collapsed position, that is drawn down to the lower end of the reamer body below the lower end of the wedge 5 in order that the tool may be passed through the casing, it being understood that when the tool is lowered below the lower end of the casing the cutters will 80 by the action of the usual spring, (not shown) be drawn upward with their inner faces against the faces of the wedge 5 until their upper ends are in contact with the abutments 6, this causing the cutters to be 85 expanded to the proper diameter to ream out the hole below the casing to the size required to permit the casing to be lowered. 90

Ordinarily as the under reamer is drawn out of the casing, as soon as the cutters are 95 above the casing they will be drawn upward on the wedge into expanded position and in order to again lower the tool into the casing the cutters must be drawn down into collapsed position and held in such position 100 until they are lowered within the upper end of the casing. Considerable care in holding the cutters in collapsed position until well within the casing is necessary in order

to prevent injury to the threads of the coupling ring 2.

The clamp of my invention consists of a ring 7 having its inner diameter the same as that of the inner diameter of the casing and having its outer diameter equal to and preferably greater than the outer diameter of the coupling ring 2 so that it will rest upon the upper edge of this coupling 10 ring. From this ring 7, and integral with it depends an annular flange 8 having its inner diameter continuous with the inner diameter of ring 7 and of the same diameter as that of the interior of the casing and 15 having its exterior diameter slightly less than the interior diameter of the coupling 2 so that when the lower edge of the ring 7 rests on the upper edge of the coupling 2 this flange 8 extends downward inside 20 the coupling nearly to the upper end of the casing and protects the threads of the coupling above the end of the casing from abrasion.

The clamp is provided with an opening 25 10 extending through the ring 7 and flange 8 preferably oblique to the axis as shown in Figure 7 so that the clamp may be readily placed on or removed from the drill rope 11 by tilting it as shown, slipping the 30 rope through the opening 10 and then turning the clamp back into normal position and permitting the flange 8 to drop into the upper end of coupling 2. This oblique slot prevents drilling line from fouling in slot, 35 while resting on coupling as shown in Figure 7 represented by dotted lines.

The clamp being thus in position on the coupling 2 and the under reamer being down in the wall below the casing, the first 40 effect of drawing the drill rope upward is that as the cutters strike the lower end of the casing they are stopped, and as the reamer body is further raised, the wedge 5 is drawn upward from between them and they move inward into collapsed position so that they can enter the casing. As the under reamer is raised through the casing the cutters are held in collapsed position by the walls of the casing. When the upper 50 edges of the cutters pass the upper edge of the upper section of the casing they enter within the flange 8 and pass nearly through the clamp. As the lower edges of the cutters pass above the upper edge of the casing 55 the force of the spring which tends to draw the cutters upward on the wedge will cause the cutters to expand outward sufficiently to force them against the walls of the flange 8 so that as the under reamer is raised further 60 to permit it to clear the casing it will carry the clamp with it and the clamp will remain in position holding the cutter in collapsed position until forcibly removed.

When the under reamer is to be returned 65 to the well its lower end is brought in line

with the casing and, as it is lowered its lower end carrying the clamp enters the upper end of the casing the flange 8 slipping down inside the coupling 2 until ring 7 rests on the upper edge of the coupling. This 70 stops further movement of the clamp and the end of the under reamer slips readily into the casing.

In Figure 5 I have shown the inner face 75 of the ring 7 coned out to form a guide for a bit 12 or for use as a funnel to guide in pouring water into the well hole.

It should be understood that the clamp is not limited to use with the Swan under 80 reamer or to use with any particular under reamer or other drilling tool with collapsible cutters as it is adapted and intended for use with any under reamer or collapsible cutter tool in which the cutters ride upward 85 into expanded position.

Having thus described my invention what I claim is:

1. A clamp for well drilling tools adapted 90 to enclose expandable cutters and hold them in closed position comprising a ring having its inner diameter substantially that of the inner diameter of the well casing, adapted to rest upon the upper edge of the coupling at the upper end of the casing and provided with means for engaging said coupling to 95 hold it concentric therewith.

2. A clamp for well drilling tools adapted 100 to enclose expandable cutters and hold them in closed position comprising a ring having its inner diameter substantially that of the inner diameter of the well casing, adapted to rest upon the upper edge of the coupling at the upper end of the casing and provided with means for engaging the inner face of 105 said coupling to hold it concentric therewith.

3. A clamp for well drilling tools adapted 110 to enclose expandable cutters and hold them in closed position comprising a ring having its inner diameter substantially that of the inner diameter of the well casing, adapted 115 to rest upon the upper edge of the coupling at the upper end of the casing and provided with an annular flange extending downward therefrom adapted to enter said coupling to hold the ring concentric therewith.

4. A clamp for well drilling tools adapted 120 to enclose expandable cutters and hold them in closed position comprising a ring having its inner diameter substantially that of the inner diameter of the well casing, adapted to rest upon the upper edge of the coupling at the upper end of the casing and provided with an annular flange extending downward 125 therefrom having its outer diameter less than the inner diameter of the coupling and adapted to enter within the screw threads thereof to hold the ring concentric with the coupling.

5. A clamp for well drilling tools adapted 130

to enclose expandible cutters and hold them in closed position comprising a ring having its diameter substantially that of the inner diameter of the well casing, adapted to rest upon the upper edge of the coupling at the upper end of the casing and provided with means for engaging said coupling to hold

it concentric therewith said ring being provided with an opening in its side oblique to its axis adapted to permit the drill rope to 10 be passed through it.

In testimony whereof I hereunto affix my signature.

FRED SWAN.
